COMPONENT CHECKING CIRCUIT FOR
BURNER CONTROL APPARATUS

Willis H. Gille, St. Paul, Minn., assignor to Minneapolis-Honeywell Regulator Company, Minneapolis, Minn., a corporation of Delaware

Application August 9, 1948, Serial No. 43,247

5 Claims. (Cl. 158—28)

1

The present invention is concerned with a fuel burner control apparatus and more particularly with that type of apparatus which will be rendered inoperative in the event that the flame fails in the burner or there is a false indication of flame by the flame detection apparatus.

In present day fuel burner controls, especially those utilizing electronic types of flame detection devices, it has been found that certain faults may occur which will result in the flame detection relay remaining energized even though the burner is no longer operative. To protect against this situation it is necessary to cause the control apparatus to be rendered inoperative in the event that there is a flame failure or a false indication of flame and this may be accomplished by energizing a safety cutoff device whenever either of these undesirable conditions exist.

It is therefore an object of the present invention to provide an improved burner control apparatus which will be rendered operative in the event of flame failure or upon a false indication of flame by the flame detection device.

Another object of the present invention is to provide an improved burner control apparatus which has a pair of transformer secondary windings for energizing a main control relay and which is maintained energized by one of the secondary windings through a circuit that includes a safety cutoff device until a flame detection relay is operated when the cutoff device becomes shunted and when the flame detection relay operates falsely the safety cutoff device is connected in an energizing circuit with the other secondary winding.

These and other objects of the present invention will be understood from a consideration of the specification, claims and the single figure of the drawing attached hereto.

The figure is a diagrammatic illustration of the control.

Referring to the single figure, the numeral 10 represents a fuel burner of any desired type. For indicating when it is desired to render the burner 10 operative, a thermostatic device 11 is provided which when actuated is effective to cause energization of the controls located in the housing 12 which in turn will cause energization of the burner 10 as long as there is indication for the need for operation of the burner by the thermostatic device 11.

The thermostatic device 11 may be seen to consist of a temperature sensing bimetal 15 which is operative to move a pair of switch blades 17 and 18 into and out of engagement with a

pair of associated switch contacts 19 and 20, respectively. These switch blades are adjusted so that they engage sequentially with blade 18 engaging contact 20 before blade 17 engages contact 19. The reasons for this will be explained in the operation portion of the specification. This thermostatic device may be located at any desired place wherein it is desired to maintain a certain temperature by means of the heat supplied by the burner 10.

Located within the housing 12 are the controls of the subject invention and supplying power to these controls is a transformer 22 which has a primary winding 23 which is connected to any suitable source of power and a pair of secondary windings 24 and 25. A burner control relay is indicated by the numeral 27 and may be seen to consist of a relay winding 28 which is operative to move switch blades 29, 30 and 31 from their deenergized position, where they are biased by means not shown, into engagement with their associated switch contacts 32, 33 and 34 respectively.

The numeral 35 represents the flame detection relay portion of the subject apparatus and may be of the type disclosed in the copending application of John M. Wilson, Serial No. 465,476, filed November 13, 1942 for "Control Device," now Patent No. 2,448,503, granted August 31, 1948. Associated with this flame detection relay is a photocell 36 which is used to detect the presence of flame emitting from the burner 10 and which is effective to cause the controls located within the boxed-in portion 37 to energize a relay winding 38. This relay winding 38, upon becoming energized, causes a switch blade 39 to be moved from engagement with a switch contact 41, where it is biased by means not shown, into engagement with an associated switch contact 40. The numerals 42 and 43 indicate input power lines to the circuits which effect operation of the relay winding 38.

A safety cutoff device 45 is provided for rendering the apparatus inoperative whenever this cutoff device has been energized for a predetermined length of time. To accomplish this type of cutout, a safety heater 46 is provided and is located so as to apply heat to a bimetal 47. The bimetal 47 is, when not energized by the heater 46, adapted to hold switch contacts 48 and 49 in the engaged position so that an electrical circuit will be completed through the contacts. If the heater 46 has been energized for a predetermined length of time the bimetal 47 will be heated and will warp toward the right from under the con-

tacts 48 and 49 and the contacts will separate. A reset actuator 50 is provided for putting the safety cutoff device back in operation after the bimetal has been warped from under the contacts 48 and 49. This actuator is of the type that prevents the contacts 48 and 49 from reengaging until such time as the actuator is released and the contacts 48 and 49 rest upon the bimetal 47. A current limiting resistor is indicated at 52 and is effective to prevent short circuiting of the secondary winding 25 whenever the burner control relay 27 becomes energized.

Operation

The apparatus as shown in the drawing is in the deenergized position and when in this position the thermostatic device 11 is not calling for operation of the burner 10 so that the burner control relay is deenergized and the flame detection relay is also deenergized. In the event that the space wherein the thermostatic device 11 is located begins to cool, the change in temperature of the bimetal 15 will cause the switch blades 17 and 18 to be moved into engagement with their associated contacts 19 and 20 respectively. The switch blade 18 will actually engage the switch contact 20 before the blade 17 engages contacts 19 as it is desired to prevent the closing of the thermostatic device from causing any chattering of the burner control relay when it becomes energized for, as will be seen from the circuit to be traced hereinafter, as soon as the blade 17 engages contact 19 and the burner control relay becomes energized, a holding circuit for maintaining the relay energized is established that is separate from this blade 17 and contact 19, this holding circuit being effective to prevent deenergization of the relay until the temperature has risen enough to cause separation of blade 18 from contact 20. When the blades 17 and 18 are engaging their contacts 19 and 20, an energizing circuit for the burner control relay 27 may be traced from the upper terminal of the secondary 24 through conductor 55, relay winding 28, conductor 56, switch contact 20, switch blade 18, switch blade 17, switch contact 19, conductor 57, switch contact 41, switch blade 39, conductor 58, resistor 52, conductor 59, secondary 25, conductor 60, heater 46, switch contacts 49 and 48 and conductor 61 back to the lower terminal of the secondary 24. As soon as the burner control relay 27 becomes energized, the switch blades 29, 30 and 31 will move into engagement with their associated switch contacts 32, 33 and 34 respectively. When the switch blades 29 and 30 engage with contacts 32 and 33 respectively, a new maintaining circuit is established for the burner control relay. This maintaining circuit may be traced from the upper terminal of the secondary 24 through conductor 55, relay winding 28, conductor 56, switch contact 20, switch blade 18, bimetal 15, conductor 62, switch contact 33, switch blades 30 and 29, switch contact 32, conductor 63, heater 46, switch contacts 49 and 48, and conductor 61 to the lower terminal of the secondary 24. It will be noted that, with switch blade 29 engaging contact 32, a shunt has been placed around the transformer secondary 25 and this shunt circuit may be traced from the upper terminal of the transformer 25 through conductor 60, conductor 63, switch contact 32, switch blade 29, conductor 64, resistor 52 and conductor 59 back to the lower terminal of the secondary 25.

When the switch blade 31 engages switch con-

tact 34 an energizing circuit is completed to the burner 10 and this energizing circuit may be traced from the input power line 66 through conductor 67, switch contact 34, switch blade 31, conductor 68, burner 10, and conductor 69 back to the other input power line 70. With the burner 10 energized, there should be a flame emitting from the burner and this flame will be detected by the photocell 36 which in turn will cause energization of the relay winding 38. With the relay winding 38 energized, the switch blade 39 will move into engagement with switch contact 40 and this will form a new maintaining circuit for the burner control relay 27 which will be independent of the heater 46 of the safety cutout device 45. This second maintaining circuit may be traced from the upper terminal of the transformer 24 through conductor 55, relay winding 28, conductor 56, switch contact 20, switch blade 18, bimetal 15, conductor 62, switch contact 33, switch blade 30, conductor 64, conductor 58, switch blade 39, switch contact 40, conductor 71, switch contact 49 and 48, and conductor 61 to the lower terminal of the secondary 24. This last traced circuit will be seen to effectively shunt out the heater for the safety cutout device 45 and this shunt circuit may be traced from the upper terminal of the heater 46 through conductor 71, switch contact 40, switch blade 39, conductors 58 and 64, switch blade 29, switch contact 32 and conductor 63 to the other terminal of the heater 46.

The apparatus is now in the operating condition with the burner 10 energized and both the relays 27 and 35 energized and while so energized the safety cutout device 45 will be effectively deenergized. The apparatus will remain in this position until such time as the heat from the burner 10 has been felt by the bimetal 15 and the temperature of the bimetal begins to rise. With the rising temperature of the bimetal, the switch blades 17 and 18 will be moved out of engagement with their associated contacts 19 and 20 so that the energizing circuit for the burner control relay 27 will be broken and this relay will become deenergized. When the relay becomes deenergized the switch blade 31, in moving out of engagement with its associated contact 34, will break the energizing circuit to the burner 10 and the burner will no longer be operative to supply flame for heating purposes. With burner 10 no longer operative the photocell 36 will not indicate the presence of a flame and the flame detector circuits, located in the box 37, will result in the deenergization of the relay winding 38 so that the switch blade 39 will move out of engagement with switch contact 40 and into engagement with switch contact 41. With both the flame detection relay 35 and the burner control relay 27 deenergized, the apparatus will be in the condition in which it is shown on the drawing and will be ready for another operating cycle.

Operation upon flame failure

Assume now that the apparatus is in its operating condition with the thermostatic device 11 calling for operation of the burner 10 and both the burner control relay 27 and the flame detection relay 35 being in the normal operating or energized position. In the event that the flame from the burner 10 should become extinguished for some reason or other, the photocell 36 will no longer indicate flame and this will result in the deenergization of the relay winding 38.

When the winding 38 becomes deenergized, the switch blade 39 moves out of engagement with switch contact 40 and into engagement with switch contact 41. With the opening of the electrical circuit between the switch blade 39 and switch contact 40, the shunt about the heater 46 is removed and a circuit may be traced through this heater from the upper terminal of the secondary 24 through conductor 55, relay winding 28, conductor 56, switch contact 20, switch blade 18, bimetal 15, conductor 62, switch contact 33, switch blade 30, switch blade 29, switch contact 32, conductor 63, heater 46, conductors 49 and 48, and conductor 61 to the lower terminal of the secondary 24. If this circuit through the heater 46 is maintained for a predetermined length of time, the heat from the heater will cause the bimetal 47 to warp toward the right so that there will be a separation of the switch contacts 48 and 49. When switch contacts 48 and 49 separate, the maintaining circuit for the burner control relay 27 will be broken and it will be impossible for the relay to remain in the energized position.

When the relay becomes deenergized the switch blade 31 moves out of engagement with its associated switch contact 34 to open the energizing circuit to the burner motor 10. The burner 10 will remain deenergized until an electrical circuit is completed through switch contacts 48 and 49 in the energizing circuit of the burner control relay 27. It will be noted that with the separation of switch contacts 48 and 49 the energizing circuit for the heater 46, traced above, is open so that the heater will become deenergized and will no longer supply heat to the bimetal 47. With the cooling of the bimetal 47, the bimetal will move toward the left. Upon depressing the actuator 50, to raise the contacts to permit the bimetal to move under the contacts, and the subsequent release of the actuator 50, there will be a reestablishing of an electrical circuit through the contacts 48 and 49, as they reengage.

With contacts 48 and 49 engaging again, an energizing circuit for the control relay will be completed and this circuit will correspond to the circuit originally traced during the discussion above on the starting of the apparatus. In the event that the reenergization of the burner control relay 27 does not result in the burner 10 producing a flame, the apparatus will become shutdown in the same manner as explained above because of the fact that the heater 46 will have an energizing current flowing therethrough and the bimetal will warp toward the right and cause the opening of the contacts 48 and 49.

From this it will be seen that the apparatus will be rendered inoperative either when there is a flame failure during normal operation or when there is a failure of combustion when the apparatus is brought into operation.

Operation upon false indication of flame

Assume now that the apparatus has been operating properly and the thermostatic device 11 no longer indicates a need for operation of the burner 10. When the bimetal 15 moves the switch blade 18 out of engagement with switch contact 20, the energizing circuit for the burner control relay 27 will be broken and the relay will become deenergized so that the burner 10 will have its operating circuit interrupted. If for any reason the flame detection relay 35 remains energized, so that the winding 38 is maintaining switch blade 39 in engagement with switch con-

tact 40 so as to give a false indication of flame, it is desired that the apparatus be rendered inoperative to prevent a further operation of the control apparatus until the fault causing false operation of the relay 35 has been removed.

To accomplish shutdown of the apparatus under these conditions it is desired to complete an electrical energizing circuit through the heater 46 and this circuit may be traced from the upper terminal of the secondary section 25 through conductor 60, heater 46, conductor 71, switch contact 40, switch blade 39, conductor 58, resistor 52, and conductor 59 back to the lower terminal of the secondary 25. Upon continued energization of this heater 46, the bimetal 47 will be warped toward the right and the switch contacts 48 and 49 will open circuit in the manner explained above. The open circuiting of the switch contacts 48 and 49 will prevent the completion of an energizing circuit through the burner control relay 27 in the event that the thermostatic device 11 should call for subsequent operation of the burner 10. It will be noted that the energizing circuit for the heater 46 was traced independently of the contacts 48 and 49 and this will mean that the heater 46 will be continually applying heat to the bimetal 47 to maintain it in its warped position. Subsequent depressing of the actuator 50 will not result in the closing of the contacts 48 and 49 for the bimetal 47 will not be in a position to permit the contacts to close when the actuator 50 is released. From this it will be seen that the contacts 48 and 49 will remain separated until the fault is cleared from the flame detection relay circuit so that the switch blade 39 will move into engagement with contact 40.

When the fault is removed from the flame detection relay, so that the switch blade moves out of engagement with switch contact 40, the energizing circuit for the heater 46 will be broken. The bimetal 47 will then cool and move back toward the left so that it will be possible to re-engage the contacts 48 and 49 upon the subsequent depressing and release of the actuator 50.

From the foregoing it will be seen that I have provided a burner control apparatus which is effective to maintain an associated burner inoperative in the event there is a false indication of flame or there is a flame failure. It may further be seen that this has been accomplished by employing a pair of secondary windings with a safety cutout device and a heater therefor connected between the windings in such a manner that the relays of the control apparatus will connect the heater in an energizing circuit with one of the secondaries upon a flame failure and with the other of the secondaries upon a false indication of flame. While I have disclosed one particular embodiment of my invention, it will be obvious to those skilled in the art that the control may be accomplished in many ways within the scope of the invention and I therefore intend to be limited solely by the scope of the appended claims.

I claim as my invention:

1. A burner control apparatus comprising in combination; a source of power comprising two transformer secondary windings; a first relay adapted when energized to cause energization of the burner; a resistor; a safety cutout device comprising an actuator and switch contacts operable when said actuator is energized a predetermined length of time to render said first relay inoperative; condition responsive means for in-

dicating the need for operation of the burner; means including said condition responsive means for connecting said first relay in an energizing circuit which includes said two secondary windings, said resistor, said cutout device actuator and said condition responsive means; means including a switch contact of said first relay when energized for connecting said first relay in a maintaining circuit which includes one of said secondary windings, said condition responsive means and said cutout device actuator; a second relay adapted to be energized upon proper operation of the burner; means including switch contacts controlled by said second relay when energized for deenergizing said actuator and for connecting said first relay in a second maintaining circuit, said second maintaining circuit including said one of said secondary windings, said condition responsive means and switch contacts of said second relay; and means connecting said actuator of said cutout device in an energizing circuit upon said second relay remaining in energized position when said first relay becomes deenergized, said means including the other of said secondary windings, switch contacts of said second relay and said resistor.

2. A burner control apparatus comprising in combination; a source of power comprising two transformer secondary windings; a first relay adapted when energized to cause energization of the burner; a resistor; a safety cutout device comprising a heater and switch contacts operable when said heater is energized a predetermined length of time to render said first relay inoperative; condition responsive means for indicating the need for operation of the burner; means including said condition responsive means for connecting said first relay in an energizing circuit which includes said two secondary windings, said resistor, said cutout device heater and said condition responsive means; means including a switch contact of said first relay when in a contacting position for connecting said first relay in a maintaining circuit which includes one of said secondary windings, said condition responsive means and said cutout device heater; a second relay adapted to be energized upon proper operation of the burner; means including contacts actuated by said first and second relays when in a contacting position for connecting a short circuiting shunt around said heater of said cutout device so that said first relay is maintained in an energizing circuit independently of said heater of said cutout device; and means connecting said heater of said cutout device in an energizing circuit upon said first relay becoming deenergized and said second relay remaining in energized position falsely indicating proper burner operation, said means including the other of said secondary windings, switch contacts of said second relay and said resistor.

3. A burner control apparatus comprising in combination; a source of power comprising two transformer secondary windings; a first relay having a plurality of switch contacts and adapted when energized to cause energization of the burner; a resistor; a safety cutout device comprising an actuator and switch contacts operable when said actuator is energized a predetermined length of time to render said first relay inoperative; condition responsive means for indicating the need for operation of the burner; means including said condition responsive means for connecting said first relay in an energizing circuit which includes said two secondary windings, said

resistor, said cutout device actuator and said condition responsive means; means including switch contacts of said first relay when in a contacting position for connecting a shunt across one of said secondary windings so that said relay is maintained energized by the other of said secondary windings in a maintaining circuit, said maintaining circuit including said cutout device actuator; a second relay having a plurality of switch contacts adapted to be energized upon proper operation of the burner; means including contacts controlled by said second relay when in a contacting position for connecting said first relay in a second maintaining circuit and for deenergizing said actuator, said second maintaining circuit including said other of said secondary windings, said condition responsive means and switch contacts of said second relay; and means connecting said actuator of said cutout device in an energizing circuit upon said second relay remaining in energized position when said first relay becomes deenergized, said means including said one of said secondary windings, switch contacts of said second relay and said resistor.

4. A burner control apparatus comprising in combination; a source of power comprising first and second transformer secondary windings; a first relay adapted when energized to cause energization of the burner; a resistor; a safety cutout device comprising an actuator and switch contacts operable when said actuator is energized a predetermined length of time to render said first relay inoperative; condition responsive means for indicating the need for operation of the burner; means including said condition responsive means for connecting said first relay in an energizing circuit which includes said first and second transformer windings, said resistor, said cutout device actuator and said condition responsive means; means including switch contacts of said first relay when in a contacting position for connecting a shunt across said first transformer winding so that said relay is maintained energized in a first maintaining circuit by said second transformer winding, said maintaining circuit including said cutout device actuator; a second relay adapted to be energized upon proper operation of the burner; means including switch contacts controlled by said first and second relays when in a contacting position for connecting a short circuiting shunt around said actuator of said cutout device so that said first relay is maintained in an energizing circuit independently of said actuator; and means connecting said actuator in an energizing circuit upon said first relay becoming deenergized and said second relay remaining in energized position falsely indicating proper operation of the burner, said means including said first transformer winding, switch contacts of said second relay and said resistor.

5. Apparatus for controlling a fuel burner, comprising in combination: a source of power comprising two secondary windings; first relay means having switch means for initiating burner operation; an energizing circuit for said first relay comprising said two secondary windings, a resistor, a safety cutout device having a heater and a pair of switch contacts, and a circuit adapted to be completed by means indicative of the need for burner operation, said switch contacts being connected in controlling relation to said apparatus such that said apparatus is rendered inoperative upon operation of said safety cutout device; a first holding circuit for said relay

closed by the energization thereof, said holding circuit by-passing said resistor and one of said secondary winding; a second relay means having switch means which are actuated upon a flame appearing at the controlled burner; means including said second relay switch means for establishing a second holding circuit for said first relay which is independent of said heater, said resistor and said one of said secondary windings and for deenergizing said heater; and means including said second relay switch means when in energized position, with said first relay deenergized, for connecting said heater in a closed cir-

cuit with said resistor and said one secondary winding.
